UNITED STATES PATENT OFFICE.

WILLIAM E. CANEDY, OF CHICAGO HEIGHTS, ILLINOIS.

DESIGN FOR A BLOWER-FRAME.

SPECIFICATION forming part of Design No. 27,518, dated August 10, 1897.

Application filed January 18, 1897. Serial No. 619,682. Term of patent 7 years.

To all whom it may concern:

Be it known that I, WILLIAM E. CANEDY, residing at Chicago Heights, in the State of Illinois, have invented a certain new and original Design for Forge-Blower Frames, of which the following is a specification, reference being had therein to the accompanying drawings.

This invention relates to a design for a frame for a blower for a forge or similar machine or structure.

The design for a frame for a blower is shown in the accompanying drawings, in which—

Figure 1 is a perspective view showing the frame in full lines and indicating in dotted lines one form of the fan-blower and driving mechanism to the end that the design may be more readily understood. Fig. 2 is a side elevation, and Fig. 3 an end elevation, of the frame.

The frame is composed of metal and may be either cast, forged, rolled, or struck up.

The base A is rectangular, having feet near the corners. The arched standards B B are attached to the base A, nearly over the feet.

These arched standards or frames are inclined toward each other at D and secured together at or near the top. The braces C C are the supports for the shaft of the driving-wheel and the fan-blower may be secured between the arches, near the bottom thereof, as indicated in dotted lines. The upper ends of the arched frames curve over above the driving-gear, forming a strong, graceful, and convenient frame to support the working parts, which are applied to the frame in about the positions indicated in dotted lines. The braces C C have the ornamental appearance indicated, and at the same time add to the strength of the structure.

What I claim is—

The design for blower-frame and support, as shown.

In testimony whereof I affix my signature in presence of two witnesses.

WILLIAM E. CANEDY.

Witnesses:

THEO. H. WIEDERHOLD,
OTTO WIEDERHOLD.
